WINDOW

Morris D. Orlin, Cleveland, Ohio

Application March 22, 1945, Serial No. 584,123

11 Claims. (Cl. 160—229)

This invention relates to storm windows and particularly to auxiliary windows that are applicable for use in conjunction with oriel type windows.

The primary object of this invention is to provide a window frame panel that is bendable at a certain point and which, when in the bended condition, is able to pass through an ordinarily restricted opening.

Another object is to provide the glass panes of a bendable window member with a transparent and flexible, weatherproof, resilient joint.

Another object is to provide such bendable window member or panel with flexible, resilient and weather-proof frame and panel members that are simple and economical to construct and which have the outward appearance of ordinary window frames and panels.

These and other objects of the invention will become apparent from a reading of the following specification and claims, together with the accompanying drawing in which like parts are referred to and indicated by like reference characters and wherein:

Figure 1 is an outside elevational view of a window having an auxiliary frame and removable panels mounted therein and which are made in accordance with this invention;

Figure 2 is an enlarged inside view of the auxiliary frame and panels;

Figure 3 is an enlarged vertical cross-sectional view of the window and auxiliary frame, taken substantially along the line and in the direction of the arrows 3—3 of the Figure 1;

Figures 4 and 5 are views similar to the view of Figure 3 and showing two typical positions that the bendable frame or panel might attain when being either inserted or removed from the main or auxiliary frame;

Figure 6 is an enlarged vertical cross-sectional view of the bendable frame, taken along the line and in the direction of the arrows 6—6 of the Figure 2; and

Figure 7 is an enlarged vertical cross-sectional view of the bendable joint between the panes of glass in the bendable frame.

Conducive to a clearer understanding of this invention, it should be pointed out that certain types of windows known as oriel windows have upper and lower sashes of different sizes. The upper sash is generally about one-half the size of the lower sash. The largest possible opening obtainable in windows of this type is no larger than the size of the upper and smaller sash. It is therefore difficult and sometimes impossible to

insert from the inside of the building the auxiliary storm windows of the prior art. The inner projection of the window sill and the lower horizontal edge of the large sash prevent the insertion of the storm window panel. Heretofore such windows had to be fitted from the outside of the building, and when it is recalled that storm windows have to be washed as well as changed at different seasons of the year, the fitting and removal sometimes create a real problem. This is especially true of windows above the ground floor that can only be reached from the outside with a ladder.

In the Figure 1 of the drawing, there is shown 15 an outside view of an oriel type casement window 12 in a building 11. The window 12 has a large lower sash 14 and a small upper sash 13. In the casement 12 there is shown mounted the storm or auxiliary window 20 having a top panel 30, a bottom panel 40, and a flexible joint 60. Each of these broadly indicated elements will be described in detail and in the order set forth.

The auxiliary window 20 is mounted on the sill 15 outside of the slideable sashes 13 and 14, 25 and fits in the frame 12 much the same as do the ordinary storm windows. The frame portion, made up of the elements 21, 22 and 24 of the storm window 20, is generally a permanent fixture and when once installed, is not removed.

30 The top horizontal piece 21 of the frame forming the window 20 has a depending flange which engages a similar flange on the top panel 30. The top piece 21 also has the pivoted holders 26 which retain the top panel 40 in place after being mounted on the hereinafter referred to hooks 25.

35 The bottom horizontal piece 22 of the frame has an ascending flange thereon which engages the bottom panel 40. This bottom piece 22 also has a ventilator 23 therein which is common in windows of this type and which forms no part of this invention.

40 The two vertical side pieces 24 which connect the ends of the horizontal pieces 21 and 22 are not flanged, but they do have means for supporting and retaining the panels 30 and 40 thereon. Specifically, the two side pieces 24 have the hook-like members, indicated by the reference character 25, which support the top panel 30; and they also have the holders 27 for supporting the bottom panels 40 and which are engaged by the lock device 52.

45 The Figure 2 shows the inside of an auxiliary window only and containing panes of glass 37

and 53-54 instead of the screens 38 and 55 of the Figure 1.

The top panel 30 consists of a rectangular frame containing either a sheet of wire mesh or screen 38 or a pane of glass 37. The top horizontal element 31 has an upwardly extending flange 32 which engages the aforementioned flanged piece 21. The bottom horizontal element 33 has a flange 34 depending therefrom which similarly engages the flange 42 of the bottom panel 40. The two side vertical elements 35 each have a tab 36 mounted thereon which engages the two hook-like members 25.

The top panel 30 is easily installed from the inside of the building by lowering the small upper sash 13 of the casement window; inserting the panel into the opening of the auxiliary window frames 20 so that the tabs 36 engage and rest on the hooks 25, and then turning the pivoted ears or cam-like holders 26 downward, as indicated.

The large bottom panel 40 consists of a rectangular frame which may contain either a screen 55 or two panes of glass 53 and 54. The top horizontal member 41 has an ascending flange 42 which engages the aforementioned flange 34. Similarly, the bottom horizontal member 43 has a depending flange 44 which engages the flanged piece 22 of the frame 20.

Each of the two side portions 45 which connect the top and bottom horizontal portions 41 and 43 are made up of two sections 56 and 57. These sections are vertically aligned as shown and have substantially abutting ends 48 and front or outer and back or inner surfaces 46 and 47 respectively.

The aforementioned abutting ends 48 are not parallel. That is, they are cut on a bias and are made so that the sections 56 and 57 touch each other at the outer surfaces 46 but are spaced apart at the inner surfaces 47. When the sections are aligned vertically, the ends 48 form a V-shaped slot.

The upper and lower sections 56 and 57 are joined together by means of a flexible metal leaf or spring 49. This spring 49 is inserted in suitable aligned grooves or slots in the sides of the sections midway between the inner and outer surfaces 46 and 47 as shown. The metal leaf or spring 49 is held in place by suitable screws 51, as shown in the Figure 6. The side portions 45 are thus able to bend inwardly as indicated by the broken lines of the Figure 6 and are caused to resume and retain their normal aligned positions because of the tension of the spring 49.

When such flexible frame is used with wire screen, only one sheet of screen need be used since the screen itself is flexible, but when glass is used, provision must be made for bending the panel at the joints or on the line between the V-shaped grooves of the two vertical side portions 45. This is provided for by using two panes of glass 53 and 54 and joining them together horizontally with a specially formed piece 60 which is made of "Lucite" or similar flexible, transparent plastic material.

The joint 60 may be manufactured easily by the extrusion process and may be cut to any desired length. In cross section, it resembles a letter H and has an upper channel 61 which receives the bottom edge of the upper glass pane 53 and an inverted lower channel 62 which receives the top edge of the lower pane of glass 54. The side walls of the channels are tapered to a relatively sharp edge, as shown, and are

made so that they grip and adhere to the pane very closely. The portion of the plastic material between the channels is sufficiently large, resilient and flexible to permit the two panes of glass to be inclined to an angle of about twenty degrees.

The bottom panel 40 may be easily inserted in the frame 20 from the inside of the building by inserting it through the relatively small opening of the main window below the sash 14. If made to bend slightly at the aforementioned joints, it will clear the sill 15, the sash 14 and fit into the space between the top panel horizontal lower portion 33 and the fixed sash 13, as shown in the Figure 4. It is then lowered so that the flanges 42 and 44 engage the flanges 34 and 21 respectively, and then is retained in place by means of the lock device 52 which engages the side holders 27.

Either of the panels 30 or 40 are removable or insertable independently of the other and it will be observed that the position of the flanges and the direction in which they extend and engage prevents rain or snow from entering at these joints.

Having thus disclosed the invention in its preferred form, it should be understood that the invention as described and illustrated is suggestive only as there may be other forms or modifications thereof which also should be considered as being within the scope of the appended claims.

I claim:

1. In a storm window, a bendable panel, comprising in combination, a frame member including top, bottom and side portions, each of the side portions having a hinge means therein, and a pane member mounted in the frame member and including a flexible joint extending laterally between each of the said hinge means.
2. In a storm window frame of the type having flanged laterally extending parts, a bendable panel, comprising in combination, a frame member including top, bottom and side portions, each of the side portions having a hinge means therein, each of the top and bottom portions having flanges thereon engageable with the aforesaid flanged laterally extending parts, and a pane member mounted in the frame member and including a flexible joint extending laterally between each of the said hinge means.
3. In a storm window, a bendable panel, comprising in combination, a frame member including top, bottom and side portions, each of the side portions having a resilient plate therein, and a pane member mounted in the frame member and including a flexible joint extending laterally between each of the said resilient plates.
4. In a storm window, a bendable panel, comprising in combination, a frame member including top, bottom and side portions, each of the side portions having inner and outer surfaces and having a leaf spring mounted therein between the said surfaces, and a pane member mounted in the frame member and including a flexible joint extending laterally between each of the said leaf springs.

5. In a storm window frame of the type having flanged laterally extending parts, a bendable panel, comprising in combination, a frame member including top, bottom and side portions, each of the side portions having inner and outer surfaces and having a leaf spring mounted therein between the said surfaces, each of the top and bottom portions having flanges thereon engageable with the aforesaid flanged laterally extending parts, and a pane member mounted in

the frame member and including a flexible joint extending laterally between each of the said leaf springs.

6. In a storm window, a bendable frame, comprising in combination, top, bottom and side portions, each of the side portions consisting of upper and lower aligned sections, and a resilient plate mounted in each of the side portions connecting the aligned sections together.

7. In a storm window, a bendable frame, comprising in combination, top, bottom and side portions, each of the side portions consisting of aligned upper and lower sections and having inner and outer surfaces, and a resilient plate mounted in each of the side portions between the inner and outer surfaces thereof and connecting the aligned sections together.

8. In a storm window, a bendable frame, comprising in combination, top and bottom portions, and parallel side portions connecting the top and bottom portions, each of the side portions consisting of aligned sections having abutting non-parallel ends and also having a resilient plate mounted in and connecting the aligned sections together whereby the side portions may bend at the said ends.

9. In a storm window frame of the type having flanged laterally extending parts, a bendable frame, comprising in combination, top and bottom portions having flanges thereon engageable with the aforesaid flanged parts, and parallel side portions connecting the top and bottom portions, each of the side portions consisting of

aligned sections having abutting non-parallel ends and also having a resilient plate mounted in and connecting the aligned sections together whereby the side portions may bend at the said ends.

5 10. In a storm window of the type having flanged laterally extending parts, a bendable panel, comprising in combination, top and bottom portions having flanges thereon engageable with the aforesaid laterally extending parts, parallel side portions connecting the top and bottom portions, each of the side portions consisting of aligned sections having abutting ends, each of the side portions also having a flexible plate connector at the said ends making the portions bendable, and upper and lower pane members mounted in the said portions, and including a flexible joint extending between the abutting ends of each side portion.

10 15 20 25 30 11. In a window frame, a side member consisting of aligned portions having inner and outer surfaces, each of the portions having contiguous non-parallel ends, the parts of the ends proximate to the outer surface abutting each other and the parts of the ends proximate to the inner surface being spaced, and a resilient plate member mounted in the aligned portions between the inner and outer surfaces thereof and connecting the non-parallel ends together and permitting the member to be bent in the direction of the inner surface.

MORRIS D. ORLIN.
